UNITED STATES PATENT OFFICE.

HARRY A. CLARK, OF CROCKETT, CALIFORNIA.

SANITARY LOAF-SUGAR DISPENSER.

1,125,653.

Specification of Letters Patent. Patented Jan. 19, 1915.

Application filed December 26, 1913. Serial No. 809,417.

To all whom it may concern:

Be it known that I, HARRY A. CLARK, a citizen of the United States, residing in the city of Crockett, county of Contra Costa, and State of California, have invented a new and useful Improvement in Sanitary Loaf-Sugar Dispensers, of which the following is a specification.

My invention relates to a sanitary loaf sugar dispenser wherein a series of rotatable compartments are formed by means of vertical flights, upon the periphery of rotatable drums and stationary horizontal shelves, each having an aperture therein, interposed 10 between the drums and the flights thereon, and each compartment having a loaf of sugar therein, the said drums being adapted to be partially rotated a distance equal to the length of one compartment for the purpose 15 of moving a loaf of sugar on each shelf into the aperture therein, thereby permitting a loaf of sugar to drop from each shelf to the shelf below it, the sugar from the bottom shelf being dispensed to the operator, and 20 the objects of my invention are first, to provide improved means for preventing the handling of loaf sugar in restaurants and other similar public places; second, to provide means for dispensing one loaf of sugar 25 at a time; and third, to provide means for replenishing an empty compartment from the shelf above it after it has been moved away from the aperture through which it 30 dispensed a loaf of sugar to the shelf below it.

I accomplish these several features by means of the device disclosed in the drawings forming a part of the present specification, wherein like characters of reference 40 designate similar parts throughout the said specification and drawings, and in which—

Figure 1 is a vertical sectional view taken on line B—B of Fig. 2, disclosing the stationary base, the rotatable base mounted thereon, the stationary shelves interposed between the drums having the vertical flights thereon, and the means for partially rotating the drums. Fig. 2 is a horizontal sectional view taken on line A—A of Fig. 50 1, disclosing the aperture in the lower flange, or shelf, the vertical flights on the drums, and a loaf of sugar in each compartment between the vertical flights. Fig. 3 is a view of the lower shelf or flange disclosing in full

lines the aperture therein and the successive 55 arrangement, or relative positions, of the apertures in the shelves above.

Referring to the drawings, the numeral 1 is used to designate a suitable stationary base having a vertical shaft 2 rotatably 60 mounted therein. The shaft 2 is provided with the reduced portion 3, the squared portion 4 and the cylindrical extension 5 on the top thereof. A rotatable base 7, having a slot 6 therein and a depending sleeve 8, is 65 rotatably mounted on the shaft 2 within the stationary base 1. The base 7 is also provided with the annular flange 9 having the aperture 25 therein, which, for purposes of better description, I shall hereinafter term 70 the lower shelf. Supported by the lower shelf or flange 9 and secured thereto in any suitable manner, is the cylindrical housing 10 within which are secured the stationary shelves 11 each having an aperture 25 therein. Interposed between the shelves 11 and 75 secured to the squared portion 4 of the shaft 2, are the rotatable drums 12 having the vertically disposed flights 14 thereon. The flights 14 divide the annular horizontal 80 spaces between the shelves 11 into rotatable compartments within each of which is placed a loaf of sugar. The lower drum 12 is provided with the inclined teeth 15, there being the same number of teeth as there are 85 flights 14, so that as one of the teeth 15 is engaged by the spring pawl 16 on the end of the arm 17 rotatably mounted upon the reduced portion 3 of the shaft 2, and moved a 90 distance equal to the length of one inclined tooth, the compartments between the flights 14 will be advanced one compartment. This is accomplished by means of the extension 20 of the lever 21, said lever 21 operating through the slot 6 in the rotatable base 7, 95 which engages a slot 18 in the arm 17, and moves the said arm 17 and pawl 16 thereon a distance equal to one tooth 15 whenever the said lever 21 is depressed, said lever 21 being returned by means of the 100 spring 23 secured to the extension 20 and the base 7. The movement of the lever 21 is limited by the length of the slot 6 in the rotatable base 7. A return movement of the drums 12 is prevented by means of the 105 pawl 30 pivotally secured to the rotatable base 7. In order to properly inclose the loaf sugar and to protect the same, I have

provided a suitable cover 28 which rests on the glass cylinder 32 surrounding the housing 10. The cover 28 is arranged to rotatably engage the extension 5 of the shaft 2.

Referring to Fig. 2 of the drawings, the drums 12 rotate to the left, or in the opposite direction in which the hands of a watch move.

In Fig. 3 I have illustrated in full lines the location of the apertures 25 in the lower shelf 9 while the dotted lines indicate the relative or successive positions of the apertures 25 in the upper shelves. That is to say, that a given vertical line of flights on being rotated, will first encounter the aperture in the lower shelf, next the aperture in the first shelf above, then the aperture in the next shelf above and so on to the top shelf. While I have illustrated only five shelves it is evident that a greater or lesser number may be used without departing from the spirit of the invention.

The operation is as follows: When the lever 21 is depressed, the extension 20 thereof, engages the slot 18 in the arm 17 and causes the pawl 16 to engage one of the teeth 15 and advance the drums 12, and the flight 14 thereon, a distance equal to one compartment. This will cause the loaf of sugar in the compartment on the lower shelf 9 adjacent to the aperture 25 therein to be moved into the said aperture, and as the lever 21 is depressed the said loaf will be dispensed thereon through the said aperture 25 above it. Simultaneously, the empty compartment which was over the aperture 25 in the lower shelf 9 will be moved under the aperture 25 in the next shelf 11 above it. Briefly, whenever the lever 21 is depressed by means of the arm 17 and pawl 16, it moves all of the drums 12 and advances all of the compartments, consequently, the compartments adjacent to the apertures will each deposit a loaf of sugar through the said aperture and into the compartment below it, while all of the empty compartments directly over the apertures will each be moved under the aperture in the shelf above it and receive a loaf of sugar through the said aperture, from the compartment above it. The rotatable base 7 is rotatably secured to the stationary base 1 so that an operator desiring a loaf of sugar can easily partially rotate the base 7 and the lever 21 therein until the same is accessible without rotating the whole machine.

It is obvious from the foregoing that I have provided improved means for dispensing loaf sugar which will effectively prevent the same from being handled, also means for dispensing one loaf of sugar at a time, and means for replenishing each compartment from the shelf above it.

While I have illustrated the square or cube loaf sugar, it is evident that a device

may be constructed which will be suitable for half cubes or slabs, without departing from the spirit of the invention.

The details of construction are so susceptible to variation, that I do not wish to confine myself to the precise construction shown herein but rather to avail myself of any modification which may properly fall within the scope of my invention.

Having thus described my invention what I claim as new and desire to secure by Letters Patent is—

1. In a sanitary loaf sugar dispenser, the combination of a stationary base; a vertical shaft rotatably mounted within the base and having a reduced portion and a squared portion thereon; a rotatable base rotatably mounted on the shaft within the stationary base, and having a slot therein and an annular flange thereon with an aperture therein; a cylindrical housing on the flange; stationary horizontal shelves secured within the housing, each shelf having an aperture therein, said apertures being arranged successively; drums having vertically disposed flights thereon and secured to the squared portion of the shaft, said flights being arranged to divide the spaces between the horizontal shelves into compartments, each compartment containing a loaf of sugar; an inclined tooth on the lower drum for each flight thereon; an arm having a spring pawl on the end thereof and rotatably mounted on the reduced portion of the shaft, said pawl being adapted to engage the inclined teeth on the lower drum; means pivotally secured to the rotatable base and operating through the slot therein and adapted to engage the arm and partially rotate the drums and cause the flights thereon to move a loaf of sugar on each shelf into the aperture therein; and means pivotally secured to the rotatable base and arranged to prevent a return movement of the drums.

2. In a sanitary loaf sugar dispenser, the combination of a stationary base; a vertical shaft rotatably mounted within the base and having a reduced portion and a squared portion thereon; a rotatable base rotatably mounted on the shaft and within the stationary base, and having a slot therein and an annular flange near the top of the said base with an aperture therein; a cylindrical housing secured to the flange; stationary horizontal shelves secured within the housing, each shelf having an aperture therein, the said apertures in each shelf being arranged successively; drums secured to the squared portion of the shaft and having vertically disposed flights thereon, said flights being arranged to divide the space between the stationary shelves into compartments, each compartment being arranged to contain a loaf of sugar, except those compartments that are immediately over an

aperture in the shelf below it; an inclined tooth on the lower drum for each flight thereon; an arm rotatably mounted upon the reduced portion of the shaft and having a slot therein and a spring pawl on the end thereof, said pawl being arranged to engage the inclined teeth on the lower drum; a lever pivotally secured to the rotatable base and operating through the slot therein, said lever having an extension arranged to engage the slot in the arm and cause the said arm to engage the teeth on the drum and rotate the flights and cause the said flights to move a loaf of sugar on each shelf into the aperture therein; means for returning the arm and lever to a normal position; and means for preventing a return movement of the drums.

5 In witness whereof I hereunto set my signature in the presence of two subscribing 15
witnesses.
